UNITED STATES PATENT OFFICE.

EDGAR M. CASKEY, OF CHICAGO, ILLINOIS, ASSIGNOR TO S. F. BOWSER & CO., INC., OF FORT WAYNE, INDIANA, A CORPORATION OF INDIANA.

DEVICE FOR CONTROLLING OIL-BURNERS.

1,102,472.

Specification of Letters Patent.

Patented July 7, 1914.

Application filed November 27, 1911. Serial No. 682,547.

To all whom it may concern:

Be it known that I, EDGAR M. CASKEY, a citizen of the United States, residing at Chicago, in the county of Cook and State 5 of Illinois, have invented certain new and useful Improvements in Devices for Controlling Oil-Burners, of which the following is a specification.

The invention relates to oil burning devices for heating furnaces and the like, and the primary object is to provide an improved mechanism for controlling the oil and air supply, whereby careless or incompetent operators may be prevented from causing explosion from the burner on account of flooding the device with oil and an insufficient supply of air to produce the proper combustible mixture.

To obtain these ends and to accomplish other new and useful objects, which will hereafter appear, the invention consists in the features of novelty and in the improved arrangement of parts described in the following specification, shown in the drawing 25 and set forth more specifically in the claims.

In the said drawing, Figure 1 is a front elevation view of the device. Fig. 2 is a plan view of the same. In both of said views the burner is shown, together with the 30 mechanism for supplying the fuel thereto and the additional mechanism for controlling the same. Fig. 3 is a sectional view through the oil supply pipe showing the details of construction of an adjustable stop 35 for limiting the movement of the oil valve operating lever.

The furnace or range to which the device is adapted to supply fuel forming no part of the present invention is omitted, since it 40 will be seen that a burner of the general form as shown more clearly in Fig. 2, and indicated by the reference character 10, may be used in connection with various forms of furnaces or ranges. Also the character 45 of construction and the means for directly controlling the burner are immaterial, in so far as the present invention is concerned, except that it is customary to arrange the burner casting 10 somewhat as shown in Fig. 2 of a conical form, or more strictly speaking, of a frusto conical form, the ori- 50 fice for the exit of the fuel being at the pointed end of the burner, and the mixing

chamber of the interior thereof being under control of a suitable hand operated valve, 55 the hand portion of which is indicated by the reference character 11 and the stem at 12.

13 is a pipe for supplying oil, and leads to a point adjacent the furnace in order to 60 communicate with the burner 10, which in the present embodiment of the invention is accomplished by threading the burner 10 into the elbow joint 14, which is provided with an air passage and in turn threaded 65 upon the upper extremity of the oil pipe 13. The same general construction is employed on the other side of the burner where the air pipe 15 approximately parallels the oil pipe 13, and is provided at its upper extremity 70 with the elbow joint 16, likewise threaded to the upper extremity thereof and to the burner 16. Both the oil and air pipes 13, 15 in the embodiment of the invention illustrated are shown passing upwardly through 75 the floor indicated at 17, although the manner of supporting these pipes, it will be apparent, will depend upon the character of installation in each instance. So much of the apparatus as has already been described 80 has been thought sufficient heretofore to supply combustible mixture to the burner 10, which is placed within the fire box of a furnace or range.

The form of burner and the accompanying details illustrated are particularly adapted for use in connection with furnaces or ranges used in cooking where it is necessary that they be operated on a large scale, and in hotels, restaurants and the like, 90 although the burner is readily adapted to be used in connection with fire boxes or furnaces and grates of various character, and in fact in almost every case where fuel oil burners may be employed.

95 Heretofore, in burners of the character described, the supply ducts such as pipes 13, 15 furnishing oil and air to the burner, have been independently valve controlled, so that an operator could admit quantities of oil 100 and air independently of each other to the burner, varying the quantities of each as desired, and admitting either oil or air independently of the other at will. Such construction has proven to be exceedingly dangerous, because careless or inefficient oper- 105

ators have in many cases caused serious explosions and injury to persons and property by admitting oil only and flooding the burner and the adjacent fire box without any or an insufficient supply of air.

It is, therefore, one of the chief objects of the invention to so construct controlling mechanism for the supply of oil and air that it shall necessitate the operator opening the air intake to the burner whenever oil is admitted, and will necessitate the cutting off of the oil supply whenever the supply of air is cut off. The oil supply pipe 13 is shown in the present embodiment controlled by a suitable valve within the valve casing 18, which is interposed between sections of the oil supply pipe 13, so that all oil passing through said oil supply pipe 13 must pass through the valve casing 18, which is provided with a valve of the design adapted to be rotated to open and close the chamber within the valve 18, the said valve not being specifically shown in the drawing, since it forms no part of the invention.

25 The outer extremity of the valve stem controlling the valve within the oil supply pipe valve casing 18 is shown provided with a suitable hand operating lever 19, securely fixed to the valve stem to rotate the same, 30 suitable fastening means as the nuts 20 on the extreme outer end of the stem being shown.

21 is a valve casing interposed between sections of the burner air supply pipe 15, the same being supplied with a suitable rotary valve not shown, being similar to the valve within the oil valve casing 18, the valve stem being indicated by the reference character 22, and having secured to its outer extremity 40 suitable operating means as the bevel wheel 23. The bevel wheel 23 is provided with gear teeth on the bevel face thereof in mesh with small operating bevel gear 24, supported on a shaft 25, which is journaled in 45 a bracket 26 sleeved on or suitably secured to air pipe 15, as illustrated, or on other convenient means of support, and at its outer extremity the shaft 25 is provided with suitable operating means as the hand wheel 50 25^a, through which motion may be imparted to the valve within casing 21 controlling air supply pipe 15. Heretofore in oil burners supplied with both fuel oil and air, the oil and air supplies have been separately controlled by independent mechanism, which has made it possible for a careless or ignorant operator to flood the furnace by shutting off the air and permitting the oil supply to remain open, frequently resulting in 55 serious accidents and destructive fires. To make such accidents impossible I provide the oil valve operating lever 19 with a lateral extension indicated at 19^a, which has its outer extremity adjacent to a lug 23^a on the 60 air valve operating bevel wheel 23. The

relative position of the lug or stop 23^a and the extension 19^a on the oil valve lever being such that they are together or approximately so when both valves are shut off, with the extension 19^a on the oil valve lever behind the lug 23^a on the air valve gear, so that any movement of an operator to open the oil valve will be resisted by the lug 23^a, and if the oil valve under such condition be forcibly opened the air valve at the same time will be opened correspondingly. This relation of the parts will also insure that the operator will first shut off the oil valve before closing the air valve, otherwise the lug 23^a will contact with the extension 19^a on the oil valve lever and close it. Therefore it will be seen that as long as the parts coöperate between the oil valve lever and the air valve gear, namely, the extension 19^a and the lug 23^a, remain intact, it will be impossible for oil to be admitted to the burner without air also being admitted and the proper mixture obtained, rendering flooding of the burner and the range to which it may be attached impossible, even at the hands of a careless or indifferent operator. The above described arrangement of the coöperating means between the oil valve lever and the air valve operating means is desirable because while the arrangement necessitates that the oil valve cannot be opened without a corresponding amount of movement being given to the air valve, yet the arrangement does not prevent the opening of the air to any amount desired without affecting the oil valve in the least, since the air valve gear 23 may be moved a complete revolution or 360° before contacting with the oil lever through the coöperating or interlocking means described. Ordinarily, it is not desired to open the oil valve lever an entire revolution, but it is preferred that the quick operating type of valve be used, which will necessitate the moving of the lever 19 through only a relatively small arc, say not, 110 for example, greater than 180°. The total permissible degree of movement of the oil valve lever 19 is preferably adjustably regulated, which may be done by securing to the oil supply pipe 13 or other suitable means of support the adjustable stop 27, which is shown in detail in Fig. 3, and in position on the device in Fig. 1, and consists of an L shaped member, as illustrated, secured to a collar 28 by machine screw 29, in such a manner as to allow the L shaped stop member to be rotated around the screw 29 as an axis. The collar 28 of the split type may be adjustably clamped in position on the oil pipe 13 by means of machine screw 30, as shown, 115 or other suitable means.

The operation of oil burners for furnaces, ranges, and the like, which are supplied with both fuel oil and air, is well understood, and the improvements of the herein described in- 130

vention do not alter the common method of operation, but only renders the same proof against accidents as long as the mechanism remains intact to operate as intended. The 5 oil burner itself may be directly controlled by means of the usual valve on valve stem 12 and operating wheel 11, and the fuel and air admitted by the fuel or oil valve lever 19 and the hand wheel 25^a for operating the 10 air valve. In devices of this character heretofore the normal operation has been to open first the air valve to admit the air to the burner, and then turn on the oil, which will insure the proper mixture, and of course 15 prevent flooding so long as air in sufficient quantities is supplied to mix with the incoming liquid fuel. The use of my device does not alter this method of operation so long as the cycle of movements is correctly 20 carried out, because if the air valve be first operated to open it, the lug or stop 23^a on the air valve operating gear 23 will be carried away from the extension stop 19^a on the oil valve lever, permitting oil valve lever 25 to be subsequently operated to admit the fuel oil. But if the operator fails to carry 30 out the proper cycle of movements in turning on the oil and air, he will either be prevented from turning on the oil or will find it necessary to put sufficient pressure upon 35 the oil valve lever to admit this air to the burner, while he will at the same time be prevented, when the burner is in operation receiving both fuel oil and air, from cutting off the supply of air without at the same time closing the oil valve.

In order that the invention might be fully understood, the details of the form of the invention best known to me have been 40 shown and specifically described, but it is not desired to be limited to the exact details of construction shown, for it will be apparent that those skilled in the art may adopt many modified forms of means without 45 departing from the purpose and spirit of the invention.

I claim:

1. The combination with an oil supply and an air supply, of means for regulating 50 said air supply to any desired extent, independently operatable means for regulating said oil supply to a certain extent, and means whereby the regulation of the oil supply may be limited correspondingly by the regulation of the air supply.

2. The combination with an oil supply and an air supply, of means for regulating 60 said air supply, means for regulating said oil supply, and means whereby the regulation of the oil supply may be limited correspondingly by the regulation of the air supply.

3. The combination with an oil supply and an air supply, of means for regulating 65 said air supply to any desired extent, and means

for independently regulating said oil supply to a limited extent determined entirely by the regulation of the air supply.

4. The combination with an oil supply and an air supply, of means for independently regulating the oil supply to a limited extent and for regulating the air supply, and means whereby the regulation of the oil supply may be limited correspondingly by the regulation of the air supply. 70

5. The combination with an oil supply and an air supply, of means for regulating said air supply, means for independently regulating said oil supply to a limited extent, and means controlled by the air supply means whereby the regulation of the oil supply is positively limited by the regulation of the air supply, said means being also adapted to prevent the closing of the air supply without first or synchronously closing the oil supply. 80

6. The combination with an oil supply and an air supply, of means for independently operating the said oil supply to a limited extent, means for independently regulating the air supply, and means controlled by the air supply means whereby the regulation of the oil supply is positively limited by the regulation of the air supply, said means being adapted to prevent the closing of the air supply without first closing the oil supply. 90

7. The combination with an oil burner, of means for supplying fuel oil to the burner, comprising an oil duct leading from the oil supply to the burner and a valve control therefor, means for supplying air to the burner, comprising a duct leading from the air supply to the burner, and being provided with a valve control, and means on the air valve control for limiting the oil supply by the regulation of the air supply. 100

8. The combination with an oil burner, of independently operable means for regulating the supply of oil and air to said burner, comprising ducts leading from the oil and air supplies and having valve controls therefor, and means on said air valve control, by the regulation of which, the oil supply may be limited by the regulation of the air supply. 110

9. The combination with an oil burner supported at the union of oil and air supply pipes of valves for regulating said oil 120 and air supply pipes, a gear wheel for operating the air valve and a lever for operating the oil valve, and means on said gear wheel adapted for engagement with said lever, whereby the regulation of the oil supply 125 may be limited by the regulation of the air supply.

10. The combination with a burner, of a pipe for supplying oil to the burner, a pipe for supplying air to the burner, valves for 130

controlling said oil and air pipes, a lever for operating the oil valve, a gear wheel for operating the air valve, and a lug or stop disposed on said gear wheel and adapted for engagement with said lever, whereby the regulation of the oil supply may be limited by the regulation of the air supply and also being adapted to prevent the closing of the air supply without first closing the oil supply.

11. The combination with a burner of a pipe for supplying fuel oil to the burner, a pipe for supplying air to the burner, valves for controlling said oil and air pipes,

a lever for operating the oil valve, a gear wheel for operating the air valve, said gear wheel being supplied with a lug or stop, and an extension on the oil valve lever adapted to engage the said lug on the gear for operating the air valve.

In testimony whereof I have signed my name to this specification, in the presence of two subscribing witnesses, on this 23rd day of November A. D. 1911.

EDGAR M. CASKEY.
